TOY IGUANA FIGURE

Charles B. Root, Morristown, N.J., assignor to Educational Design Associates

Filed May 8, 1972, Ser. No. 251,568

Term of patent 14 years

Int. Cl. D21—01

U.S. Cl. D34—2 R

FIG. 1

FIG. 2

FIG. 3

FIG. 1 is a perspective view of the rear, top and right side of a toy iguana figure showing my new design.

FIG. 2 is a bottom view.

FIG. 3 is a left side elevational view.

FIG. 4 is a front elevational view.

I claim:

The ornamental design for a toy iguana figure, substantially as shown.
